United States Patent Office

Des. 232,608
Patented Sept. 3, 1974

232,608

COSMETIC VANITY

Viola Darrow, Cleveland, Ohio
(P.O. Box 64, Gibsonton, Fla. 33534)

Filed Dec. 11, 1972, Ser. No. 313,648

Term of patent 14 years

Int. Cl. D6—04
U.S. Cl. D6—160

Fig 1

Fig 4

Fig 5FIG. 1 is a front and right side perspective view of a cosmetic vanity showing my new design;

FIG. 2 is a left side elevational view;

FIG. 3 is a rear elevational view;

FIG. 4 is a top plan view; and

FIG. 5 is a front and right side perspective view of a second embodiment of a cosmetic vanity showing my new design wherein doors are provided.

The bottoms of both embodiments are plain and unadorned.

I claim:

The ornamental design for a cosmetic vanity, as shown and described.
